HAIR COMB

Kenneth G. Sonntag, Chicago, Ill.

Application April 11, 1947, Serial No. 740,781

8 Claims. (Cl. 132—11)

1

This invention relates to novel and useful improvements in hair curlers and particularly those which might be classified as "non-thermal."

An object of this invention is to provide an improved hair comb characterized by means for curling hair.

Another object of this invention is to provide adjustable teeth means, which are resiliently biased to the adjusted position.

Another object of this invention is to provide means for adjusting and regulating said resilient adjusting means.

A further object of this invention is to provide means for manually adjusting the relative position of the teeth of the comb.

A still further object of this invention is to provide an extremely simple and efficient hair curling device which is both efficient in operation and inexpensive to manufacture.

Ancillary objects and features of novelty shall become readily apparent to those skilled in the art, in following the description of the preferred embodiment of the present invention, illustrated in the accompanying drawings, wherein:

Figure 1 is a longitudinal sectional view of the preferred form of the present invention, parts being shown in elevation for descriptive purposes;

Figure 2 is a bottom view of the preferred form of the present invention;

Figure 3 is a perspective view of the invention disclosed in Figures 1 and 2;

Figure 4 is a transverse sectional view of the invention disclosed in Figure 2 and taken substantially on the line 4—4 thereof and in the direction of the arrows, and

Figure 5 is a transverse sectional view taken substantially on the line 5—5 of Figure 1 and in the direction of the arrows.

This invention has been developed to provide a device, exclusive of external sources of power (electric, thermal, etc.), for the purpose of providing curl in persons' hair. It is common knowledge that equal and opposite forces applied to a strand of hair, thence drawing said hair through or from between said forces, will cause said strand of hair to result in a curl. This invention is devised to operate on this principle of operation.

A housing 10, composed of any suitable material such as plastic, metal or the like, is provided with a bore 12 therein. A portion of said housing is formed to provide a handle while the remainder of the housing is provided with longitudinally and transversely aligned teeth de-

2

pending therefrom, two end teeth being integrally connected (Figures 2 and 5). These teeth are indicated at 16. A piston rod 18 is received in said bore 12 extending substantially the full length of the teeth portion of said housing. A row of teeth 20 integral with said piston rod depends between said rows of teeth 16.

There is provided in the handle portion of said housing means for resiliently biasing said piston rod. The preferred form of resilient biasing means is a simple coil spring 22, shown clearly in Figure 1. It is seen that a collar or flange 24 is provided about said piston rod and is adapted to abut a shoulder 26 in the said bore 12. By this construction, a limiting means is provided for the said piston rod. The other end of said spring 22 engages a conventional hex nut or threaded collar 28 which is received in said bore. It is noted at this point that the end portion of the said bore 12, designated by the numeral 30, is of complementary cross section to the periphery of the hex nut. By this expedient, the said hex nut 28 is limited in rotational movement and is permitted substantially only movement parallel to the axis of the said bore. A screw 32 is received in the end portion of the said housing 10 and the threads thereof engaged the conventional threads of the hex nut 28. It is quite obvious that upon rotation of the screw 32, the hex nut may be selectively adjusted longitudinally of the bore 30. It is further apparent that by this expedient, the potential energy, stored in the resilient biasing means 22 may be selectively adjusted. A collar 34 is secured to, or formed integral with the shank of the said screw 32 and is rotatably received in a suitable complementary configured recess 36. This recess retains the collar 34 and consequently the screw 32 in a selected, predetermined position permitting no axial movement of said screw. This construction permits rotation of the said screw yet obviates any longitudinal movement axially thereof. A suitable hook or hanging means 38 is supplied at the thermal portion of said screw for conveniently storing the invention when not in use.

In operation, a lug 40, rigidly secured to the piston rod 18 is urged in a selected position to adjust the relative position of the teeth 16 and 20 thereby permitting the teeth of the comb to be pulled through the hair without any noticeable extra effort. After the comb is partially pulled through said hair the lug 40 is released and permitted to be urged through the confines of the slot 42, provided in the housing 10, there-

by causing strands of hair to be engaged between the outer rows of teeth 16 and the inner row of teeth 20. Thence the comb is pulled farther through the hair, thus curling the same as described hereinabove. It is noted from an inspection of Figure 1 that a second slot 44 is provided in the piston rod 18 and a second lug 46 extends therethrough. It is quite apparent from an inspection of this figure, that this slot and lug construction provide limiting means and guide means for said piston rod relative to the housing 10. The preferential construction for this lug is to project the same through the said housing thereby aiding in manufacture.

There has been described and illustrated but a single preferred embodiment of the present invention, capable of performing all of the specifically mentioned objects as well as ancillary objects. However, it is apparent to those skilled in the art, that various changes including omissions, additions and rearrangement of elements may be made herein without departing from the spirit of the invention. Accordingly, limitation is sought only in accordance with the scope of the following claims.

Having thus described the present invention what is claimed as novel and improved is as follows:

1. A hair curler comprising a housing having a bore therein, transversely and longitudinally aligned teeth fixed to said housing, a piston rod in said bore, a row of teeth on said piston rod extending between said aligned teeth, resilient means for biasing said rod axially of said bore to oppose the operation of said rod, means for adjusting the compression of said resilient means, means for actuating said piston rod, said compression adjusting means comprising an internally threaded collar slidably received and fixed with respect to rotation in said bore and having said resilient means in abutment therewith, a threaded arm in said threaded collar for adjustably sliding said collar in said bore, and means operatively connected with said arm and said housing for preventing axial movement of said arm.

2. A hair curler comprising a housing having a bore therein, transversely and longitudinally aligned teeth fixed to said housing, a piston rod in said bore, a row of teeth on said piston rod extending between said aligned teeth, resilient means for biasing said rod axially of said bore to oppose the operation of said rod, means for adjusting the compression of said resilient means, means for actuating said piston rod, said compression adjusting means comprising an internally threaded collar slidably received and fixed with respect to rotation in said bore, a threaded arm in said threaded collar for adjustably sliding said collar in said bore, said resilient biasing means including a spring abutting said rod and said collar, and means operatively connected with said arm and said housing for preventing axial movement of said arm.

3. A hair curler comprising a housing having a bore therein, transversely and longitudinally aligned teeth integral with said housing, a piston rod in said bore, a row of teeth on said piston rod extending between said aligned teeth, resilient means for biasing said rod axially of said bore to oppose the operation of said rod, means for adjusting the compression of said resilient means, means for actuating said piston rod, said compression adjusting means comprising an internally threaded collar having said

resilient means in engagement therewith and slidably received and fixed with respect to rotation in said bore, a threaded arm in said threaded collar for adjustably sliding said collar, said piston rod actuating means including a slot in said housing, a lug secured to said rod and projecting through said slot, and means operatively connected with said arm and said housing for preventing axial movement of said arm.

4. A hair curler comprising a housing having a bore therein, transversely and longitudinally aligned teeth integral with said housing, a piston rod in said bore, a row of teeth on said piston rod extending between said aligned teeth, resilient means for biasing said rod axially in said bore to oppose the operation of said rod, means for adjusting the compression of said resilient means, means for actuating said piston rod, said compression adjusting means comprising an internally threaded collar axially slidable and fixed with respect to rotation in said bore, a threaded arm in said threaded collar for adjustably sliding said collar, said resilient means including a spring abutting said rod and said collar, said piston rod actuating means including a slot in said housing, a lug secured to said rod and projecting through said slot, and means operatively connected with said arm and said housing for preventing axial movement of said arm.

5. A hair curler comprising a housing having a bore therein, transversely and longitudinally aligned teeth integral with said housing, a piston rod in said bore, a row of teeth on said piston rod extending between said aligned teeth, resilient means for biasing said rod axially in said bore to oppose the operation of said rod, means for adjusting the compression of said resilient means, means for actuating said piston rod, said compression adjusting means comprising an internally threaded collar slidably received in said bore and fixed with respect to rotation in said bore, said resilient means engaging said collar, a threaded arm in said threaded collar for adjustably sliding said collar, said arm having a flange fixed thereto, and said housing having a recess seating said flange to prevent axial movement of said arm.

6. A hair curler comprising a housing having a handle portion with a bore, and an annular recess in said handle portion, transversely and longitudinally aligned teeth integral with said housing, a piston rod in said bore, a row of teeth on said piston rod extending between said aligned teeth, resilient means for biasing said rod axially of said bore to oppose the operation of said rod, means for adjusting the compression of said resilient means, means for actuating said piston rod, said compression adjusting means comprising an internally threaded collar slidably received and fixed with respect to rotation in said bore, said resilient means engaging said collar, a threaded arm in said threaded collar for adjustably sliding said collar within said bore, and said arm having a flange secured thereto which is rotatively disposed in said recess to prevent axial movement of said arm in said bore.

7. A hair curler comprising a housing having a bore therein, a piston rod in said bore, teeth attached to said rod and to said housing in juxtaposition to each other, resilient means for biasing said rod axially of said bore to oppose the operation of said rod, means for adjusting the compression of said resilient means, means for actuating said piston rod, said compression adjusting means comprising a threaded collar

slidably received and fixed with respect to rotation in said bore, said resilient means engaging said collar, a threaded arm in said threaded collar for adjustably sliding said collar, means operatively connected with said arm and the bore of said handle for preventing axial movement of said arm in said bore.

8. A hair curler comprising a housing having a bore therein, a piston rod in said bore, teeth attached to said rod and to said housing in juxtaposition to each other, resilient means for biasing said rod axially of said bore to oppose the operation of said rod, means for adjusting the compression of said resilient means, means for actuating said piston rod, said compression adjusting means comprising an internally threaded collar slidably received in said bore and fixed with respect to rotation therein, said resilient means engaging said collar, a threaded arm in said threaded collar for adjustably slid-

ing said collar, said housing having a handle portion with an annular recess in said handle portion, an annular flange secured to said arm and disposed in the annular recess in said handle portion to prevent axial movement of said arm in said bore.
